JOHN LE DROIT LANGDON, OF ROCHESTER, NEW YORK, ASSIGNOR TO GENERAL RAILWAY SIGNAL COMPANY, OF GATES, NEW YORK, A CORPORATION OF NEW YORK.

SLOTTED SIGNAL-LEVER.

1,152,370.

Specification of Letters Patent. Patented Aug. 31, 1915.

Application filed August 30, 1911. Serial No. 646,914.

To all whom it may concern:

Be it known that I, JOHN LE DROIT LANGDON, a citizen of the United States, and resident of the city of Rochester, in the county of Monroe and State of New York, have invented a new and useful Slotted Signal-Lever, of which the following is a specification.

This invention relates to railway electric signaling and particularly to devices and arrangements of circuits for controlling what is known in the art of railway signaling as a semi-automatic, power operated, dynamic indication signal.

The object of this invention is to construct and arrange a system by means of which a railway signal of the ordinary automatic block semaphore type may be controlled semi-automatically without any change in the arrangements and constructions of the signal itself, but such changes and arrangements as are needed to cause it to operate semi-automatically will be made in the interlocking machine by which it is controlled.

Railway signals may be controlled manually, automatically, and semi-automatically. A manual signal may be either mechanically operated as by means of pipes or wires, or may be power operated as by means of electricity or compressed air, in which case the operation of the signal is controlled by controlling the flow of either electricity or compressed air to the operating means at the signal. Automatic signals are, in general, operated either by electricity or compressed air, the movements of the signal being controlled wholly by the movements of trains upon the tracks controlled by the signals. A semi-automatic signal is a signal which is

not only controlled manually but is also controlled by the movements of trains upon the track controlled by the signal. A semi-automatic signal may be moved to the clear position manually through the medium of connecting wires or pipes and restored to danger by the passage of a train acting to deenergize an electromagnet which forms a connecting link in the connecting wire or pipe; such a signal is ordinarily called a slotted signal on account of its similarity to antiquated types of signals controlled from two different points. Semi-automatic signals are also in use which are moved to the clear position by the operation of electricity or compressed air which is controlled manu-

ally by a leverman in a tower as at an interlocking plant.

The type of semi-automatic signal which is herein described is designed to be operated by electricity which is controlled manually. It is further of the type of electrically operated signals which are designed to generate a current of electricity when the semaphore arm returns to the danger position by reason of its bias and to thereby effect a release of locking in the interlocking machine of which the lever controlling it, is a part, such release locking being known ordinarily as a return indication. Heretofore in signals of this type, in order to obtain a return indication it has been necessary to resort to the movement of a weight which was raised at the same time that the signal was cleared and was held suspended even after the semaphore arm returned to the danger position was not allowed to drop until the lever controlling the signal in the tower was returned to the normal indicating position, at which time the operating current holding the weight in suspended position was cut off and then by the falling of the weight, an indication current was generated. Such signals were rather crude and clumsy in their construction and quite complicated.

A standard form of operating mechanism which is applicable to all situations in which an electrically operated semaphore may be used is highly desirable, but on account of the fact that an electrically operated semaphore, used as an automatic signal, requires no mechanism for generating a return indication current, it is necessary when such a signal is employed in an interlocking plant as a semi-automatic signal with a return indication, to provide means by which the current may be obtained. The problem is further complicated by the fact that when such a signal is controlled from the commonest and best known electric interlocking machine, the lever controlling the signal is in the reverse position when the semaphore returns to the danger position by the entrance of a train into the block controlled thereby and for such reason even if an indication current is generated, the lever in the machine is not in the proper position to make use of such indication as is well understood by those skilled in the art; furthermore the ordinary and well known method of breaking the control wire for the signal through

the front point of a track relay controlled by the section governed by the signal, is not applicable to a signal of the type herein described, for the entrance of a train into the section governed by the signal deenergizes the track relay and so breaks the continuity of the control wire, consequently, even if an indication current is generated by the signal upon returning to the danger position, no path back to the interlocking machine is open to it, consequently, means other than those commonly used must be resorted to in a signal of the type herein set forth.

In the accompanying drawings by which the invention is illustrated and in which like characters of reference refer to like parts, Figure 1 is a side elevation of a lever of an interlocking machine adapted for controlling a semi-automatic signal, with one side of the lever guide removed. Fig. 2, is a section on the line A—B of Fig. 1, looking in the direction of the arrow; Fig. 3 is a section on the line C—D of Fig. 1, looking in the direction of the arrow; Fig. 4, is a section on the line E—F of Fig. 1, looking in the direction of the arrow; Fig. 5 is a section on the line G—H of Fig. 1, looking in the direction of the arrow; Fig. 6, is a diagrammatic representation of the circuits employed in this invention.

Numeral 1, designates a lever guide which is adapted to guide and support the lever 2, and to support the associated mechanism, such guides being well known to those skilled in the art and being merely one of a series which are assembled to form an interlocking machine, the machine locking by which the predetermined movement of the levers in proper sequence is determined, being governed by a tappet connected to the pin 3, which pin is given a vertical reciprocating motion upon the movement of the lever by reason of the cam slot 4 in the lever. The ordinary and well known lever latch is designated by 5, and serves to control various circuits to be hereinafter described. The first movement in clearing a signal by means of the lever 2 would be to grasp the handle and raise the end 6 of the latch 5, thus causing the reciprocatable member 7 to move upwardly, thus causing bent spring member 8, which rests in a groove therein, to also be moved upwardly, thus causing the end 9 to contact with the member 10. Both members 9 and 10 are insulated from each other and from the frame work of the lever as by insulating means 12 and 11, thus normally no circuit is closed therethrough, but upon the just described movement a path is afforded from contact 13 to contact 14, said contacts being designated in the same manner in Fig. 6. The frame 17 which supports member 7 and insulating blocks 11 and 12, is supported itself by the lever guide 1, fastened thereto by the screw 18 also sup-

ports a solenoid 19 which incloses a movable core 20 and a fixed core 21. The movable core 20 is fastened to a rod 22 which passes through the fixed core 21 and is attached to one end of a crank 23, the other end of which is attached to a reciprocating bar 24, the other end of the bar being supported by an arm 25. The energization of the solenoid 19 causes a magnetization of the fixed core 21 and a magnetization of the movable core 20, thus causing movable core 20 to move upwardly into contact with fixed core 21 and so withdraw the lower end of the movable core 20 from within a notch 26 in the top face of the lever 2. While the movable core 20 rests in the notch in the top face of the lever 2, it is impossible to move the lever. The bar 24 carries the carbon blocks 27, 28, 29, 30 and 31, which are adapted to contact with springs 32, 33, 34, 35, 36, 37, 38, 39, 40, 41, either in their normal position or in their reverse position and the springs 32 to 41 inclusive are connected each separately to binding posts upon an insulating block 42 carried by the frame 17, one row of the binding posts being shown in Fig. 1, the separate binding posts being designated by numerals 43 to 47 inclusive.

Beneath the lever 2, but in the same plane therewith, is pivoted a latch 48 on the pin 49, and having a shouldered projection 50 on one end thereof adapted when moved upwardly to lie in the path of the shouldered projection 51 upon the lever 2, after the lever has been moved toward the reverse position. It also has a projecting end 52, which lies in the path of a dog 53 so that when the dog by the movement of the lever in moving to reverse position contacts with the projection 52, the other end 50 of the latch 48 is moved upwardly so as to lie in the path of the shouldered projection 51 of the lever and so prevent the return of the lever to the normal position until the latch has returned to its normal position. The lever also bears the dog 54, pivoted on a pin 55 and resiliently held in its normal position as shown by the springs 56, which dog is adapted upon a movement to reverse position of the lever to contact with a tooth of the ratchet wheel 57 and so rotate the ratchet wheel against the tension of the spring 58. Just as the dog 53 completes the upward movement of the end 50 of the latch 48, the dog 54 engages with a tooth on the ratchet wheel 57 and so rotates the ratchet wheel that a tooth thereof engages with the dog 60 to throw the upper end of the said dog underneath the end 50 of the latch 48 and so hold the latch 48 in its moved position against the tension of the spring 61 tending to return it to normal position. The spring 61 also bears upon one arm of dog 60 in such manner as to tend to move the other end of the dog 60 underneath the end 50 of the

latch 48, so that a positive actuation of the dog 60 is required after it has once been thrown under the latch 48 to remove it therefrom. The means for removing the end of the dog 60 from beneath the latch 48 is the rod 62 which is attached to an armature 63, which is held in the position shown by means of screws 64 which pass through holes therein and fasten into the cores 65 of the electromagnet 66. When the electromagnet 66 is energized by an indication current as herein after described, the armature 63 is raised into contact with the cores 65 and so causes the rod 62 to be raised, striking one arm of the dog 60, causing the other arm of the dog to be thrown out from beneath the latch 48, thus allowing the spring 61 to return the latch to the normal position as shown in Fig. 1. Although the movement of the latch 48 as hereinbefore described takes place upon a movement of the lever to the reverse position, that is, in the direction of the arrow J, no movement of the latch 48 takes place when the lever is returned to the normal position, for the dog 53 being pivoted upon the pin 67 and spring held by the spring 68 in the normal position as shown in Fig. 1, passes over the end 52 of the latch 48 when the lever is being returned to the normal position without causing a movement of latch 48 on its pivot 49 by reason of the fact that the spring 68 allows the dog 53 to rotate on its pivot 67 out of the path of the end 52 of the latch 48. It is also to be observed that the dog 54 causes no rotation of the ratchet wheel 57 when it contacts therewith upon a movement of the lever 2 toward the normal position after being moved to reverse position, for, upon being returned to the normal position, the end of the dog 54 when it contacts with ratchet wheel 57, which is prevented from turning easily by spring 58, is caused to rotate on its pivot 55 out of the path of the teeth on ratchet wheel 57, it being able to do this by reason of the cut-away portion 69 in the lever 2.

To those familiar with the art the lever and associated mechanism just described will be recognized as a modification which in fact it is, of the lever and indicating mechanism shown, described and claimed in a patent to John D. Taylor, 752,127, February 16th, 1904, but it will also be recognized by those skilled in the art that whereas in the Taylor patent above mentioned, the indication and lever mechanism co-operating therewith is so designed that both upon the movement of a lever toward reverse position and toward normal position, an indication current must be received through the indication magnet before the full stroke of the lever can be completed, in the present case, however, as the shoulder "13" of the Taylor patent above mentioned, is not present, it is not necessary to receive an indication cur-

rent through the electromagnet 66 upon a movement of the lever to the reverse position in order to complete the full stroke of the lever. The most important difference, however, is the fact that in order to make use of the return indication current flowing through the indication magnet as shown in the Taylor patent above mentioned, it is necessary to have the lever at either the reverse indicating position or the normal indicating position, but in applicant's invention if the lever is in the full reverse position and the indication current is received through the indication magnets 66, the latch 48 will be caused to move into the position shown in Fig. 1, withdrawing the end 50 from the path of the shouldered projection 51 of the lever 2, and as the dog 53 does not cause the end 50 of the latch 48 to move into the path of the shouldered projection 51 of the lever 2 when the lever is moved toward the normal position, it is not necessary to have the lever in the normal indication position when the indication is received in order to complete the stroke of the lever to the normal position, but in the Taylor patent, above mentioned, if the lever is in the full reversed position when the indication is received, a later movement of the lever toward the normal position will result in a shoulder upon the latch "9" of the Taylor patent moving into the path of the shoulder "14" of the Taylor patent, thereby preventing the full movement of the lever toward the normal position and it is necessary, therefore, to cause the indication current to flow through the indication magnet "16" of the Taylor patent, after cut-away portion "24" of the Taylor patent has arrived, to a position over the projection "23" of the latch "9" of the Taylor patent. This fundamental difference between the operations of the two types of levers has caused the present type to be called the stored indication type as the indication may be received while the lever is in the full reverse position and be available at any future time.

In the diagrammatic representation of the circuits involved in this invention as shown in Fig. 6, 19 represents diagrammatically the solenoid as shown in Fig. 1, the contacts 9 and 10 correspond to the contacts 9 and 10 of Fig. 1 and the numeral 24 designates the oscillating bar as shown in Fig. 1, the bar being shown in Fig. 6, in its normal position so that carbon block 27 makes contact with the two wires 70 and 71, whereas the other carbon blocks do not make contact with wires. Carbon block 31 has not been shown in the diagrammatic representation in Fig. 6, because the required number of contacts are obtained without the use of it, but with a three position signal, the same would be used; 72 and 73 designate conducting members of which 73 is adapted to

make contact with springs 74 and 75 in the normal position of the lever and is adapted to break contact therewith upon the initial movement of the lever. Conducting block 72 contacts with springs 76 and 77 at the normal position of the lever and also at the position called the normal indication position which is the position at which the lever as shown in the patent to Taylor 752,127 above mentioned, is stopped and at which an indication is received before the lever can be put in the full normal position in moving from the reverse position to normal position; springs 78 and 79 are adapted to be contacted and connected together by the conducting block 72 at the reverse indicating and full reverse positions of the lever. Both conducting blocks, 72 and 73 are connected together and to the rod 80 shown in Fig. 1, which rod being connected to the lever 2 causes the blocks 72 and 73 to move in unison therewith; 66 designates diagrammatically the so called indication magnet which is also shown in Fig. 1; 81 designates a source of electric current; 82 designates a section of railway track, the movement of trains thereover being controlled by the semaphore arm 83, both of the rails 84 and 85 being insulated in the well known manner from the alining rails at the end of the section and a battery 86 being connected to both rails at one end and a relay 87 having an armature 88 being connected to the two rails at the other end. The semaphore arm 83 is moved to the clear position by means of a motor of which 89 designates the armature having the brushes 90 and 91 bearing thereon, the semaphore being connected to the armature by the shaft 92; 93 and 94 designate the operating coils of the fields, and 95 and 96 designate the holding coils of the field; the motor being so designed that operating current entering the motor through wire 97 will flow through coils 93 through wire 98, will flow through all of the coils 93 to 96 inclusive and so cause the motor to rotate and move the semaphore to the clear position but current entering through the wire 98, will flow through all of the coils 93 to 96 inclusive and so hold the semaphore arm 83 in its moved position.

99 designates a conducting strip which is normally in the position shown and which is adapted to conduct current from brush 100 to brush 101 and which is further adapted to break contact with brush 100 and 101 when the semaphore arm is moved to the clear position; 102 designates a conducting member which is adapted to connect brushes 103 and 104 at the moment the signal reaches the clear position or just before, so as to cause the current to flow through all of the field coils.

All of the parts as shown in Fig. 6, are in the normal position, but when the lever 2 is reversed, blocks 72 and 73 move in the direc-

tion of the arrow K and reciprocating bar 24 moves in the direction of the arrow M when the solenoid 19 is energized and returns by gravity to the position shown when the solenoid is deenergized. The first movement in reversing lever 2, would be to actuate the latch 5, having the arm 6 thereby causing contacts 9 and 10 to come together, which, if no train were in the track section 82, would allow current to flow in the following path: positive side of battery 81, wire 105, wire 106, armature 88, wire 107, wire 108, spring 75, block 73, spring 74, wire 109, contact 13, wire 110, spring 9, contact 10, contact wire 111, wire 112, solenoid 19, wire 16, wire 113, wire 114, to the negative side of the battery 81. Current in the above traced path would energize the solenoid 19, causing it to lift the movable core 20 thus unlocking the lever, at the same time it would oscillate bar 24 so that all of the contacts which are shown open would be closed and the contacts which are shown closed would be opened so that the current which flowed through wire 107 in the above traced path through the conducting block 73, would now have a path from wire 107, through wire 115, carbon block 30, wire 116 to wire 112 and thus to and through the solenoid and back to the negative side of the battery in the path just above described. It is thus seen when the lock is once picked up, it is held up by what is called the stick contact, so that even if the connection between contacts 9 and 10 were broken the lock would still remain energized. As soon as the lock has been energized and the movable core 20 raised and the lever released, it may be moved to its full reverse position thereby connecting springs 78 and 79 so that current would flow in the following path: positive side of battery 81, wire 105, wire 117, spring 79, conducting block 72, spring 78, wire 118, carbon block 29, wire 119, carbon block 28, wire 120, wire 121, wire 122, contact spring 100, block 99, contact spring 101, wire 97, wire 124, field 94, wire 125, brush 90, armature 89, brush 91, wire 126, field 93, wire 127, and wire 114 to the negative side of the battery. The current flowing in the above traced path would cause the motor to operate and move the semaphore arm 83 in the direction of the arrow N to the clear position at which point contacting strip 99 would disconnect springs 100 and 101 and contact strip 102 would connect springs 103 and 104 so that the current as above described flowing to springs 100 and 101, would then flow from wire 122 to wire 129, spring 103, contact strip 102, spring 104, and wire 98, field 96, wire 123, field 95, wire 130, wire 124, field 94, wire 125, brush 90, armature 89, brush 91, wire 126, field 93, wire 127, and wire 114 to the negative side of the battery. The current flowing in the

above traced path would as heretofore set forth hold the semaphore arm 83 in the moved position.

If while the parts were in the position as above described a train should enter upon section 82, the relay 87 would be shunted, armature 88 would drop thus breaking contact with wire 107, consequently the circuit through the solenoid 19 would be broken and consequently the movable core 20 would drop thus causing the bar 24 to oscillate in a direction contrary to the arrow M; such a movement of the oscillating bar 24 would break the contact between wire 118 and the carbon block 29, consequently the holding current would be cut off from the motor and consequently the semaphore arm 83 by reason of its bias would return to the danger position driving the motor backward and thus generate a current, which current, due to the fact that carbon block 27 connects wires 71 and 70 would flow in the following path, bearing in mind, that the semaphore, in returning to danger position closes the contact between springs 100 and 101; brush 91, wire 126, field 93, wire 127, wire 113, wire 131, indication magnet 66, wire 132, wire 70, contact block 27, wire 71, wire 121, wire 122, spring 100, contacting strip 99, spring 101, wire 97, wire 124, field 94, wire 125, to the other brush 90 of the motor and then through the armature to the brush 91. The current flowing in the above traced path would cause the rod 62 to strike against one arm of the dog 60, causing the other arm of the dog to be thrown out from under the latch 48 the end 50 of which was raised into the path of the shouldered projection 51 of the lever 2 by the act of reversing the lever. It will thus be seen that the mechanism for preventing a return of the lever to normal position, has by the current which flowed through the magnet 66, rendered the means for preventing the return of the lever to the normal position ineffective and that it has accomplished this object while the lever was in the full reverse position, so that at any time after the indication has been received the manipulator of the levers may return the lever.

It is to be observed that the breaking of the circuit through the solenoid 19, while the lever was in the reverse position prevented the making of that circuit again even if the relay 87 were again energized until the lever 2 had been returned to the full normal position, for the solenoid 19 is a stick solenoid as heretofore pointed out and the pick-up circuit for the same must be made through the circuits 74 and 75, which cannot be done unless the lever is in the full normal position, so that it is necessary for the leverman to return the lever to full normal position after the entrance of a train upon section 82 in order to again clear the

signal and if the lever is returned to the full normal position while the train which caused the signal to go to the danger position is still in section 82, it would be impossible for the leverman to again clear the signal while the train was in section 82, for, it would then be impossible to energize the lock through the pick-up circuit, for it would be broken under such conditions at the armature 88 which would be in its lower position caused by the presence of a train upon the rails of section 82. It is very essential that the lever should thus operate, for, if the leverman were able to reverse the lever while a train was in section 82, he would cause the latch 48, having the end 50, to move into the path of the shouldered projection 51 on the lever, but as it would be impossible to clear the signal with a train in section 82, he would then have the lever reversed with the latch up and the signal in the danger position so that there would be no way of energizing the electromagnet 66 to release the latch in order to return the lever so that he would have to resort to a prohibited practice, namely, the so-called picking of the indication which would simply amount to a manual operation of latch 48. In order to prevent the reversal of the lever with a train in section 82, the carbon block 30 is so placed upon reciprocating block 24 that it will not make contact with wires 115 and 116 until the movable core 20 has reached a position one thirty-second of an inch removed from its final lower position, thus rendering certain that the end of the movable core 20 will have been seated in the notch 26 in the top face of the lever 2 before it is possible to again make the pick-up circuit for the solenoid 19 complete.

It is necessary to provide means whereby the lever 2 may be replaced in the normal position after being reversed, thus causing the movement of the semaphore arm 83 to the danger position if no train accepts the signal and moves upon section 82 for which reason, if the lever 2 is returned to the normal indication position after being moved to the reverse position on account of the holding circuit through the motor being broken at the springs 78 and 79, the arm 83 will move to the danger position and the lever being in the normal indication position a circuit will be formed as follows: brush 91, wire 126, field 93, wire 127, wire 113 and wire 131, indication magnet 66, wire 132, spring 76, block 72, spring 77, wire 122, spring 100, contact strip 99, spring 101, wire 97, wire 124, field 94, wire 125, and to brush 90, thus completing the circuit, the current in which, generated by the movement of the armature caused by the movement of the signal to the danger position, causes the indication magnet 66 to be energized and the rod 62 to be

raised, thus releasing the dog 60 from beneath the latch 48 and allowing the lever to be moved to the full normal position.

Having thus explained the principle of my invention and described one particular physical embodiment thereof, what I claim as new and desire to secure by Letters Patent, is:

1. In an interlocking machine, a lever having a normal position, a reverse position and a normal indication position, a projection on the lever, a pivoted spring pressed latch adjacent the lever, a spring held wiper pivoted on the lever, a shoulder on the lever abutting one side of the wiper the free end of the wiper being adapted to contact with one end of the latch and thus rotate it on its pivot, raising the other end, a projection on the other end of the said latch, a spring pressed pivoted dog adapted to be forced under the raised end of the latch and to hold the latch in its moved position, with the projection on the latch in the path of the projection on the lever for stopping the lever at normal indication position when being moved from reverse toward normal position, a centrally pivoted member having equidistantly spaced projections, each projection adapted to come in contact with said dog to force it under the latch, a pivoted finger on the lever spring held in one position, a shoulder on the lever adapted to abut the side of one end of said finger, said finger adapted to engage a projection on the said centrally pivoted member and force a projection of said centrally pivoted member in contact with the dog, a fixed shoulder against which the pivoted finger abuts when the lever is in normal position, an electro-magnet having an armature and a rod connected thereto which rod is adapted to strike said dog and release said latch when said electro-magnet is energized, and means to energize said electro-magnet.

2. In a signaling device, a lever adapted for movement in two directions having a normal position, a reverse position and a normal indication position, a signaling device governed partly by the lever when moved into reverse position, a wiper carried by the lever, means actuated by said wiper while the lever is being moved to reverse position to prevent its return in the other direction beyond the normal indicating position, said wiper being ineffective when the lever is moved from reverse position toward the normal position, and means actuated by the return of the signaling device from operated condition while the lever

is in reverse position to allow said lever to complete its stroke to full normal.

3. In a device of the class described, a controlling lever adapted for movement to a plurality of positions, one of said positions being a normal position, another of said positions being a normal indication position, another of said positions being a full reverse position, stop-means to prevent the lever from being returned to the normal position after being placed in the full reverse position, and means including an indication device capable of rendering said stop-means ineffective when the lever is in the full reverse position to allow said lever to be moved to full normal.

4. In a device of the class described, a lever adapted to be reciprocated, a pivoted latch, means to raise the latch upon a movement of the lever in one direction only, while leaving the latch unmoved when the lever moves in the opposite direction, means to hold the latch in the raised position, said lever having a part coöperating with the latch when in raised position to prevent the return of the lever to full normal position, and means acting while the lever is moved from the normal position to release the latch.

5. In a signaling system, a signal having a plurality of positions, two means acting jointly to cause said signal to assume one position, one of said means including a movable member having a plurality of positions, a movement to one of said positions causing in conjunction with the other means the clear position of the signal, means preventing the full return of the movable member from one extreme position to the other, actuated by the said movement to one of said positions of the movable member, the other means of the two said means operating to render said preventing-means ineffective and to permit said movable member to move continuously from one extreme position to the other.

6. In a signaling device, a signal, means to move the signal including a member adapted to move, means to prevent said member from returning to normal position, means for causing the signal to return to the position from which it is moved, and means actuated thereby to render the second named means inoperative, and permit said member to move continuously from one extreme position to the other.
